UNITED STATES PATENT OFFICE.

HAROLD E. WHITE, OF SCHENECTADY, NEW YORK, ASSIGNOR TO GENERAL ELECTRIC COMPANY, A CORPORATION OF NEW YORK.

BLOCK-SIGNAL SYSTEM.

No. 799,816.

Specification of Letters Patent.

Patented Sept. 19, 1905.

Application filed February 11, 1904. Serial No. 193,086.

To all whom it may concern:

Be it known that I, HAROLD E. WHITE, a citizen of the United States, residing at Schenectady, county of Schenectady, State of New York, have invented certain new and useful Improvements in Block-Signal Systems, of which the following is a specification.

My invention relates to block-signal systems; and the object of my invention is to provide a novel signal system comprising as one of its elements a novel form of relay which remedies a defect in operation which has existed in such systems as heretofore arranged.

In a block-signal system in which home and distance signals are used it is customary to operate the relays for the home signal for a given block from the same source of current which operates the distance-signal for the following block, the home signal being controlled by an ordinary relay the operation of which depends merely on the flow of current regardless of direction and the distance-signal being controlled by a polarized relay the operation of which depends upon the direction of the current. In this arrangement in order to secure the proper operation of the polarized relay it is necessary that the current through it should be reversed when the distance-signal is to operate. This necessitates a reversal of current through the relay for the home signal also, and during the reversal of flux there is an instant when the flux is zero, which produces a momentary shifting of the home signal. This shifting of the home signal may under some circumstances cause the engineer of an approaching train to stop his train wholly unnecessarily. By my invention this shifting of the home signal upon the operation of the distance-signal is done away with and the chance of needless stops eliminated.

My invention will be best understood by reference to the accompanying drawing, in which--

A A' A² represent three blocks of a railway system.

B and B' represent two semaphore-posts at the entrance to blocks A and A', respectively. Each semaphore-post carries a home and distance signal, (indicated by H and D, respectively.) Thus the home signal for block A is indicated by the semaphore-arm H on semaphore-post B. The distance-signal for the same block is indicated by semaphore-arm D' on semaphore-post B'. The drawing indicates

the position of the signals on the assumption that a train is in block A. The relay E is short-circuited, allowing its armature *e* to fall. This opens the circuit of the operating mechanism for the home signal H, allowing the signal to go to danger position by gravity. The operating mechanism for signal H is merely indicated by *m*, since many forms of electrical operating mechanisms are well known in the art and form no part of the present invention.

Home signal H controls by its movement reversing-switch S in the circuit of battery *b*, which supplies the current for the relays connected to block A'. When home signal H is in the danger position, switch S is in the proper position to produce a flow of current through polarized relay F' of proper direction to deenergize the relay and to open the circuit of the operating mechanism *n'* of distance-signal D'. Thus home signal H and distance-signal D' are in the proper position to show the presence of a train in block A. Current is flowing through relay E', which operates regardless of the direction of current-flow. Relay E' thus holds its armature up and maintains the circuit of operating mechanism *m'* closed. Home signal H' is accordingly held at "safety," properly indicating that block A' is clear. Now assume that the train in block A is passing out of the block and into the one beyond. The short circuit is removed from relay E, which draws up its armature *e* and closes the circuit of operating mechanism *m*, which restores signal H to "safety." As signal H moves to safety position it draws up switch S and reverses the direction of current through the track-circuit A'. Polarized relay F' is thus energized and draws up its armature *f'* and operating mechanism *n'* restores distance-signal D' to "safety." Signals H and D' are then in the proper position to show that block A is clear; but in reversing the current through relay F' the current through relay E' is also reversed. This produces a reversal of flux in relay E', during which there is an instant when the flux is zero. At this instant armature *e'* falls, opening the circuit of operating mechanism *m'*, and consequently signal H' goes to "danger" by gravity. Although signal H' is restored to its proper position the next instant, there is a chance that the engineer of an approaching train may glance at the signal

at the instant it goes to "danger." Upon seeing a home signal at "danger" the engineer may apply the emergency-brake, thinking a train to be in the block he is entering, 5 while in reality the train is two blocks beyond, and a stop is wholly unnecessary. This defect in the operation of the system is eliminated by the novel form of relay which I employ for controlling the circuit of the operating mechanisms for the home signals. It will 10 be seen from the drawing that relays E and E' each consist of an E-shaped magnetic core, forming with the armature two magnetic parts or circuits, on one part of which is mounted the coil *i*, which is connected to the track-circuit. The coil *i* corresponds to the relay-operating coil as ordinarily used. In addition to coil *i* two other coils *j* and *k* are placed upon the core E. Coil *j* is placed on 15 the same portion of the core as coil *i* and being in inductive relation thereto acts as a secondary for coil *i* and is energized by any fluctuation of current in coil *i*. Coil *k*, which is mounted on the other part of the core forming 20 the second magnetic circuit, is connected in series with coil *j* and is traversed by any current induced in coil *j*. The operation is then as follows: Assuming the circuit of coil *i* to be opened suddenly, the variation in magnetic flux produced by the sudden variation 25 of current induces an electromotive force in coil *j* which causes a current to flow through coil *j*. This current produces a magnetization of the portion of the core on which coil *k* is mounted, which is displaced in phase 30 from the magnetization produced by coil *i* and maintains armature *e* in its raised position during the instant that the magnetization of coil *i* passes through its zero value. The 35 effect of coil *k* is of course only instantaneous; but by the time its effect has died away coil *i* is again energized and continuously maintains armature *e* in its raised position. The effect of coil *k* therefore serves to bridge 40 over the instant during which coil *i* is deenergized by the reversal of current. Consequently all danger of the signal controlled by relay E going to safety position upon an instantaneous reversal of current is eliminated 45 and a serious defect in operation is removed.

While I have shown a simple form of relay well adapted to secure the object of my invention, it will be understood that its form may be considerably altered without departing 50 from the spirit of my invention. For instance, although I have shown two magnetic circuits having one part in common, it is not necessary that they should possess this feature, and the shape of the magnetic circuits 55 may be much altered without affecting the operation. Accordingly I do not desire to limit myself to the particular construction and arrangement of parts here shown, since changes which do not depart from the spirit 60 of my invention and which are within the

scope of the appended claims will be obvious to those skilled in the art.

What I claim as new, and desire to secure by Letters Patent of the United States, is—

1. In combination, an electric circuit, a switch member adapted to open said circuit, a relay adapted when energized to maintain said switch member in its closed position, a coil adapted to energize said relay, and a second coil arranged to be energized upon a variation of current in the first-named coil and adapted to maintain said circuit closed during an instantaneous reversal of current in the first-named coil. 70

2. In combination, an electric circuit, two relay-coils, two magnetic circuits arranged to be energized by said coils, respectively, means operative upon the energizing of either coil for maintaining said circuit closed, a source of current connected to one of said coils, and means for energizing the other coil upon a variation of current in the first coil. 80

3. An electric circuit, two relay-coils, means operative upon the energizing of either coil for maintaining said circuit closed, a source of current connected to one of said coils, means for reversing the relative connections of said coil to said source, and means for energizing the other coil upon a reversal of current in the first coil. 90

4. In combination, two magnetic circuits, a movable armature adapted to be restrained when either magnetic circuit is energized, a coil mounted on one of said magnetic circuits and connected to a source of current, and a second coil mounted on the other magnetic circuit and arranged to be energized upon a variation of current-flow in the first coil. 100

5. In combination, two magnetic circuits, a movable armature adapted to be restrained when either magnetic circuit is energized, a coil connected to a source of current and adapted to energize one of said magnetic circuits, and means for energizing the second magnetic circuit upon a variation of current-flow in said coil. 105

6. In combination, two magnetic circuits, a movable armature adapted to be restrained when either magnetic circuit is energized, a coil mounted on one of said magnetic circuits and connected to a source of current, a second coil arranged to be energized inductively upon a variation of current through said coil, and a third coil mounted on the other magnetic circuit and connected in series with the second coil. 115

7. A block-signal system, comprising a block-circuit, a source of current therefor, a polarized relay connected to said circuit, means for reversing the current through said circuit, and a non-polarized relay connected to said circuit and comprising two coils each adapted when energized to maintain said relay closed, one of said coils being connected to said circuit and the other coil being ar- 125

ranged to be energized upon a reversal of current through the first coil.

8. A block-signal system, comprising a block-circuit, a source of current therefor, a polarized relay connected to said circuit, means for reversing the current through said circuit, and a non-polarized relay connected to said circuit and comprising two magnetic circuits each adapted when energized to maintain said relay closed, a coil connected on one of said magnetic circuits and connected to the block-circuit, a second coil arranged to be energized inductively upon a variation of current through the first coil, and a third coil mounted on the other magnetic circuit and connected in series with the second coil.
9. A block-signal system, comprising a block-circuit, a source of current therefor, a polarized relay connected to said circuit,

means for reversing the current through said circuit, and a non-polarized relay connected to said circuit and comprising two magnetic circuits each adapted when energized to maintain said relay closed, a coil connected on one of said magnetic circuits and connected to the block-circuit, a second coil arranged to be energized inductively upon a variation of current through the first coil, and a third coil mounted on the other magnetic circuit and connected in series with the second coil.

In witness whereof I have hereunto set my hand this 9th day of February, 1903.

HAROLD E. WHITE.
